UNITED STATES PATENT OFFICE

MAURICE CHARLES HENRI OCTAVE LECOCQ, OF CAMBRAI, FRANCE

WEAVING LOOM

Application filed October 1, 1928, Serial No. 309,638, and in Belgium October 5, 1927.

The present invention has for its object mechanical arrangements which allow, in weaving looms, a spent shuttle to be removed and to be replaced by another without the speed of the loom being slackened and without any trouble being caused to the normal functioning of the loom.

It has previously been proposed to effect the automatic changing of the shuttle, and for this purpose the rear wall of the shuttle box has been pivoted, and adapted to be released from a detent, on the weft failing or the shuttle pîrn becoming substantially exhausted, by the weft-fork or weft-feeler, so that it can be swung inwards by a spring, across the path of the shuttle, and the spent shuttle diverted and ejected from the machine at a subsequent pick. The box-front is then raised and a fresh shuttle enters the shuttle box under the raised box-front.

The present invention relates to automatic shuttle-changing apparatus of the above type and its main objects are to ensure the security of the locking device, to increase the reliability of the shuttle-changing operation, to render the walls of the shuttle box quite rigid during the normal operation of the loom, and to avoid any damage to the mechanism, even if the fitting of this mechanism or the loom is bad. The invention is essentially characterized by the back of the shuttle box being firmly maintained in its normal position, in spite of the action of a spring which tends to open it by pivoting, by a detent which may only be released during a very short period of each cycle, when the lay is in the forward or beating up position, because a stop fixed on the breast beam of the loom then lightly pushes back the box-back, just enough to allow the tooth of the detent to be disengaged from its groove. At this moment a member situated on the lay itself can release the detent, transmitting to it, by means of a flexible intermediate member, an impulse produced by the action of the weft fork or feeler. As the locking or unlocking members are all on the moving part of the loom (lay), consequently they cannot be harmed in movement, nor can any untimely unlocking be produced. Moreover, at alternate beats of the loom, when

the shuttle box already contains a shuttle, the releasing of the detent is absolutely prevented by a cam or a member of the loom, which prevents any action of the weft fork on this detent thus preventing the opening and the deviation of the back part of the box, and avoiding the grave danger of the projection of a shuttle outside of and in front of the loom. The arrangement for changing the shuttle is again characterized by the locking of the front part of the shuttle box on the back part in order to keep it rigidly lowered during the normal operation of the loom, and by another locking in order to retain this front part in a raised position during the introduction of a new shuttle. The invention is again characterized by various arrangements for safety or improvement, avoiding any damage to the members, even in case of bad fitting of the loom, and allowing the mechanism to be adapted to any loom without having to vary its characteristics, its speed and its fitting in any way.

In order that the invention may be more clearly understood it will now be described with reference to the accompanying drawings which show an automatic shuttle-changing mechanism adapted to a weaving loom with a fast reed and under the control of the weft fork or feeler.

Figure 1 is a plan view of the device.

Figure 2 is a sectional view along the line A—A in Figure 1.

Figures 3, 4, 5 and 6 represent respectively, on a slightly larger scale, the sectional views along the lines B—B, C—C, D—D, of Figure 1, and the end view.

Figure 7 shows a detail of the apparatus.

Figure 8 shows an accessory arrangement.

Referring to the drawings, 1 is the breast beam of the loom, 2 is the movable lay, supported by its two oscillating levers or swords 3, and 4 is the reed fixed to the lay.

A shuttle box is fixed on one of the ends of the lay and comprises the following members: a base plate 5 (wherein the grooves 6 of the shuttle-driving picker is formed), a back part of the shuttle box 7 (shown partly in section in Fig. 1) which is pivoted to this plate by a pivot 8; a box-front 9 connected

by two arms 10, a crosspiece 11 (sectional in Fig. 1) and two supports 12 to a rotatable shaft 13 in two parts carried by two supports 14 and 15 rigid with the base plate. A spring (here a helical spring 16 working by torsion around the pivot 8, see Fig. 6) tends to move the back of the box and make it occupy the inclined position shown by broken lines in Fig. 1. In the normal operation, the back of the box is kept in its normal position by a tail piece 18 (Fig. 3) the end of which engages with a detent 19 fixed to the lay, or preferably to the base plate 5. This detent 19 is itself, by means of its spur 20, under the action of a flexible lever 21 pivoted on the change shaft 22 fixed behind the lay and extending the entire length of the reed. At the other extremity of the reed the change shaft 22 carries (Fig. 2) another lever 23 which can be struck, in order to turn it a little, by a small bar 24 added to the usual weft fork 25 of the loom. This fork 25 is articulated at the end of a support 26 rigidly fixed to the breast beam 1.

The back of the box is pushed back into the normal position every time the lay approaches the breast beam (Fig. 3), by an abutment 27 placed at the extremity of a forwardly projecting push rod 28 carried by the extremity 30 of the pivoted box-back. This box-back is extended at 29 towards the end of the lay and on the other side of the pivot 8, and the member 29, (Figs. 1 and 6), during the opening by pivoting, engages, by means of a small rod 30, with a spur fixed to the support 12 of the box-front. The opening of the box-back thus provokes the lifting of the box-front up to the position represented in broken lines in Figs. 4, 5 and 6. The small rod 30 pushes the spur by means of the forked end, (Fig. 6), but does not draw it back.

When the box-front is raised, it locks itself in a high position (Fig. 4) due to a detent 31, carried by the support 15, which engages with the supporting member 32 fixed to the box-front. The unlocking of the box front is effected by the abutment 33 secured to the box-lock when the latter returns to its normal position, by striking the tail piece 34 of the detent 31. The box-front then falls again, and again locks itself, in the normal position, by means of its other detent 35 fixed to the member 9 by a flexible strip (Fig. 3). In effect, this catch 35 engages under the staple 36 carried by the tail piece 28 of the box-back when the latter is reclosed.

The pivot 13 of the box-front also carries, at one end, (Fig. 6), a cam 37 which moves with it. This cam causes a transfer lever 38, pivoted on an axis 39 fixed to the support 14, and carrying a roller 40 at its front end, to move from the position shown in full lines to that shown in broken lines. This raised transfer lever 38, moving with the lay towards the breast beam of the loom, engages on ap-

proaching the breast beam with the lever 41 of a supply magazine carried by the breast beam of the loom and moves it from its former position before contact with the approaching transfer lever, position shown in full lines, to that shown in dotted lines. The supply magazine essentially comprises, on a base plate 42 (Figs. 1 and 4), a shuttle chamber 43, the bottom of which can be swept by a push bar 44, operated by means of the spur 45 of the charging lever 41, and the lever 41 so rolls on a curved supporting surface 46 that when the end contacting with the roller 40 moves towards the left as shown by the position in dotted lines in Fig. 1, the other end carrying the spur 45 moves to the right and with it the push bar 44 and the new shuttle to be used. The curvature of the supporting surface 46 is such that the push bar imparts to the shuttle a uniform or slightly accelerated movement, and not a movement decreasing in speed as that of the lay. This prevents the new shuttle being pushed forward by the push bar from moving quicker than the said push bar and tilting over, as would be the case if the movement of the push bar was proportionate to that of the lay, when, at the decrease in speed, the shuttle, not being retained, could run in advance thereof.

It is necessary again to point out, before explaining the operation of the apparatus, that the interior of the box-back contains (Fig. 1) the braking tongue or swell 47 usually existing on weaving looms with a fast reed, and on which the shuttle coming into the box acts. This swell is pivoted on the pivot 48 fixed to the box-back and, by means of its tail piece 49 which here extends through the lay (see Fig. 5), acts in the known manner on the lever 50 fixed to the stop rod and the tongue for stopping the loom. The unusual position of the pivot 48, oscillating towards the exterior, and of the lever 50, transported towards the end of the loom, will be noticed. A second braking tongue 51, specially for the ejection, is also pivoted on the pivot 48 and is returned by an independent spring, (not shown), against a fixed or movable stop 52 on the end of the lay: this tongue can act equally through its tail piece 52 on the lever 50 and the tongue for stopping the loom.

The other members or details will be mentioned in the course of the explanation of the operation of the apparatus.

When the weaving loom is running in a normal manner with a full shuttle, all the members occupy the positions represented by full lines. The back of the shuttle box is firmly retained by its detent 19 (Fig. 3), which engages, as will be noticed, with a backwardly inclined tooth, formed on the member 18. At each beat up or pick in the forward position of the lay, the abutment 27 of the box-back engages with the breast beam

and makes the end of the box-back move somewhat backwards on the lay (two millimetres for example), so that at this moment (position in broken lines to the right in Fig. 3) the tooth of the detent 19 would be able to be easily disengaged from the groove. This detent, however, is kept raised by a small spring, and does not disengage from the tooth if the small bar 24 of the weft fork does not act, through the lever 23, on the change shaft 22; the box back then remains locked when the lay is withdrawn.

The small bar 24 (Fig. 2) can act on the lever 23, on the change shaft 22 and consequently on the catch 19 when the weft fork is not subjected to any exterior action, as its normal position is shown in broken lines in Fig. 2. When the shuttle arriving in the box opposite, has left behind itself a fiber or weft thread 53 interposed between the reed 4 and the prongs 25 of the fork, this weft thread causes the weft fork to lift in the well-known manner, so that the small bar 24 passes underneath the mouth of the lever 23, 20 without striking the latter. The following beat up or pick, when the shuttle is in the box already described and when there cannot be any weft thread between the reed and the prongs of the weft fork, it is necessary to 25 prevent the impact of the bar 24 on the lever 23. This is effected by raising the tail piece of the weft fork by means of the roller 54, mounted on the fixed pivot 55, and controlled by the lever 56. This lever receives 30 its movement from a cam (not shown) mounted on the usual shaft (wiper shaft) which, on all looms, turns at half speed, cam regulated for thus lifting the roller, one turn out of two turns, when the lay is forward or beating up. For this purpose can be used the 35 already existing cam which operates the hammer of the fork. As long as the loom then functions normally, the shuttle enters into the box already described where it acts as already explained on the swell 47, and consequently on the lever 50. Then it is projected again normally by the usual shuttle driving picker 57 of the loom.

The failing of the weft thread 53 sets the 50 mechanism into operation. The small bar 24 then strikes the lever 23 which it carries along a little (for 5 millimetres for example) and thus rotates the change shaft 22. With this shaft (Fig. 3) turns the flexible lever 21. The 55 latter presses on the spur 20 fixed laterally to the detent 19. At first the latter is strongly engaged by its tooth in the groove in the tail piece 18 of the box-back. The lever 21 has not enough force to lower it and can only 60 bend itself against this resistance. When the lay, continuing its forward motion, releases the detent 19 from its groove, as previously explained, the bent lever 21 lowers the detent 19. On the following withdrawal of the 65 lay, the detent 19, still held downward, allows

the box-back 7 to be deflected smoothly under the action of its spring 16, since the detent 27 remains in contact with the breast beam till the box-back has been completely deflected.

On being moved, the tail piece 28 of the box-back commences to disengage the staple 36 of the catch 35 of the box-front, and releases the same. Then the small rod 30 operates the box-front, as already stated, and lifts it. The box-front takes the position 75 represented by the broken lines of Figs. 4, 5 and 6, and locks itself in the high position through the detent 31, as has already been explained. Likewise, the cam 37 raises the transfer lever 38 to the horizontal position. All these movements are produced when the abutment 27 leaves the breast beam, that is to say, about after the first half-course backward of the lay.

Then, when the spent shuttle is thrown towards the box, it finds the box-back moved. It engages, on slanting a little, behind the rear surface of this member, between the latter and the braking tongue 51. It acts on this tongue as on an ordinary braking swell, pushing its backwards, which thus also moves the lever 50. The ejected shuttle remains at first thus tightened in between the back of the box 7 and the tongue 51, being also supported in part by the base plate 5. If the ejected shuttle were stopped in its course, in front of the lay-sword 3 for example, the lever 50 would not be moved, and the loom would be stopped by its stopping tongue.

The lay returning in the forward direction, the groove of the roller 40 then operates the lever of the magazine (Fig. 6 in broken lines), causing it to turn, in spite of its spring, and operate the push bar 44. The latter engages with the bottom shuttle of the supply magazine and projects it forward whilst the lay advances. The shuttle passes under the uplifted box-front (Fig. 5). At the same time, the abutment 27 has again engaged with the breast beam, and the back of the box is restored to the normal position. At the end of the forward movement of the lay, the replaced box-back is locked again by 19, the shuttle is fully pressed into its box by means of the push bar; the box-front, released by the abutment 33, again falls and closes in the new shuttle; on falling again it is locked by 35 and 36. The ejected shuttle has been pushed back by the back of the box 10 off the base plate. The braking tongue 51, pivoted backwards with the box-back, has again engaged with its aforesaid fixed stop 52 on the lay. This movement has been regulated and the stop 52 chosen so that this movement increases the distance which separates the back of the box-back from the tongue 51 so that all pressure on the ejected shuttle is removed; the latter, no longer having a support or brake, falls and clears this space. (If 100

a stop 52, as represented in Figs. 1 and 6, is not sufficient for this purpose, a movable stop as explained hereinafter may be used.) When the lay withdraws, the push bar 44 moves backwards under the action of a return spring and allows a fresh unused shuttle to fall to the bottom of the supply magazine. The lever 41 also resumes its normal position; the roller 40 is disengaged from it and again falls into the normal position. All is ready for a further operation.

In Fig. 6, represented by 58, is a movable abutment for assuring that the ejected shuttle is released when the box-back is pushed back into its normal position. This abutment 58 is pivoted at 59 on the exterior support 14, and a spring tends to lower it into the position shown in broken lines. By means of its arm 60, this abutment is lifted by the cam 37 in the normal position (thick lines). During the charging operation, the deviated cam 37 allows the abutment 58 to be lowered on to and supported by the working extremity of the braking tongue 51. The latter, on being pushed back by the ejected shuttle, allows the abutment 58 to drop slightly again so as to lock the tongue 51 (position in broken lines) by means of its front notch. When the tongue 51 is then deflected backwards with the box-back, its working end cannot return towards the stop 52 and the pressure on the ejected shuttle is thus removed and the latter then able to fall. Then, the cam 37, on moving again, raises the arm 60 and thereby the movable abutment 58, and thus allows the tongue 51 to return to its stop 52 in order to be ready to brake another ejected shuttle.

The mechanism can, if desired, be accompanied by various arrangements of improvement and safety.

In order to retain at the bottom of the supply magazine the first new shuttle to be introduced without it being released, two catches 61, mounted at the end of the two flat bars 62 which are pivoted on a pivot 63 on the base plate underneath the push bar, are used, (Figs. 1 and 4). A spring tends to lift each bar 62 with the catches 61. When the push bar advances before engaging with the new shuttle, it commences by passing over small ramps 64 carried by each flat bar; this movement causes the bars to be lowered and disengages the catches 61 from the shuttle; the push bar then engages with the shuttle. The result of this is that if such an untimely charging was made, the shuttle already ejected from the supply magazine would be able to re-enter it, pushed back by the box-front, by passing over the catches 61. In this case, it is necessary that the push bar 44 may be able to withdraw in spite of the effort of the roller 40 on the lever 41. To this end, the lever 41 is broken at 65 by an articulated joint with an abutment 66, which a spring (not shown)

tends to render rigid, but which, nevertheless, is capable of yielding in case of any excessive effort. In the same way, in order to allow the re-entry into the bottom of the magazine of such an ejected shuttle, it is necessary to prevent the descent of an upper shuttle on to the push bar. To this end, when the push bar advances, a ramp 67, which it carries, engages with the rollers 68 of one or two levers flexibly pivoted at 69; these apply stops 70 to the upper shuttle, which form a brake on this shuttle, and retain it in the suspended position until the push bar has returned to its waiting position; then only can the liberated shuttle fall to the bottom of the magazine, if this place is free.

Fig. 7 represents an arrangement for allowing the shuttle-driving picker 57 to return to the end of the lay to facilitate the introduction of a new shuttle. This picker is usually stopped before the end of its course by a resistance (check strap or spring) which generally pushes back the shuttle coming normally against it. In order to bring back the picker itself during the changing of a shuttle, the movement of the ejected shuttle is used in the following manner. The resistance which retains the picker is joined to a bent lever pivoted at 71, of which the long arm 72 comes behind the picker 57, and of which the short arm 73 can be moved by the braking tongue 51; a spring 74 (or a check strap) tends to return the bent lever to the position represented in full lines. In normal operation, nothing whatever opposes the free movement of this bent lever. When, however, a shuttle is ejected, the deflected tongue 51 presses against the arm 73 of the lever, and releases the picker. The ejected shuttle, on stopping against a stop 75 on the arm 72, also helps this movement.

The picker can also be brought back, if it has stopped in operation, by pushing it by its lower part underneath the base plate (Figs. 1 and 5) by means of a lever 76 mounted on a pivot 77 fixed to the lay. Another lever with a grooved roller 78 abuts against, when necessary, an oscillating plate 79 fixed to the supply magazine, lever 78 being pivoted and adapted to move the lever 76 with it (by means of a flexible intermediate member for avoiding damage); a spring then returns the whole to its normal position, removing the lever 76 from beneath the groove 6 of the driving picker. The oscillating plate 79 is controlled by the swinging charging lever 41; in the normal position, it is not on the path of the grooved roller 78, but when the swinging lever is displaced for effecting a charge, it causes plate 79 to oscillate (see Fig. 5), and puts it into a suitable position to cause the levers 78 and 76 to be pivoted.

In Fig. 1, in section, and in front of the lay sword 3, and in Fig. 4, is to be seen a tongue 80 which is also mounted on the pivot 48.

- This tongue crosses the rear wall of the box-back near its end. When this box back moves forwards, the tongue 80, pushed by a spring 81, projects slightly. The ejected shuttle at first engages with this spring-pressed tongue which yields and deadens the impact, helping the ejected shuttle to move into its oblique direction towards the ejecting box without any jolt.
- 5 In the case when the charging of a shuttle is controlled by the weft fork, the lay beats up once, twice or three times, without any weft thread being inserted in the fabric, the quality of the latter suffering therefrom. To
- 10 avoid this defect, the movement of the fabric, by means of the ordinary take up or regulator, is stopped during one, two or three picks, as judged best. For this purpose, the arrangement represented by Fig. 8 is used.
- 15 The counter-pawl of the regulator can be lifted by means of an intermediate member (not represented) employing the motion of the magazine lever or the push bar. It is known that the advancement of the fabric is
- 20 produced by the alternative movement of a pawl 82, which participates in the movement of the lay, in order to rotate a ratchet wheel, the reverse rotation of which is prevented by a counter-pawl 83. Suspended from the
- 25 pivot 84 on the counter-pawl 83, is a partially polygonal member 85 having small projections at its points, preferably rollers such as 86, 87, 88. Normally, the counter-pawl and the suspended member occupy the position represented in broken lines. When a
- 30 shuttle-charging operation is effected, the mechanism lifts the counter-pawl, so that the member 85, moved by its weight or a spring, swings in the direction of the arrow *a* until
- 35 it occupies the position represented by thick lines and then again falls on the pawl: the counter-pawl is thus retained in the air. The pawl 82, however, still executes its to and fro movements. It carries a projection such
- 40 as 89 adapted to engage with the projections or rollers 86, 87, 88 and to move them along in one direction (to the left in the figure), but not in the other. The first semi-oscillation to the left pushes 87 to the position of
- 45 86, but the following one towards the right does not bring it back because the inclined member 89 slides underneath the rollers 87 and 88 resting on the pawl through the weight of the counter-pawl. At the following beat of the loom, the roller 88 is, in its turn, pushed to the left, so that the member 85, no longer having sufficient support, swings in the direction of the arrow *b* and allows the counter-pawl 83 to return in gear. By
- 50 raising the number of projections or rollers, the counter-pawl can be kept raised during more than two beats, as desired. The member 85, or a similar member, can alternatively be suspended from the movable pawl and
- 55 rest upon the counter-pawl.

It is well understood that many substantial variations may be applied to the invention. For example, the change shaft 22 between the weft fork and principal detent can occupy any other position on the lay; the box-back 70 can be fitted with any other kind of spring; the stops can occupy other positions; the pivotal points of the two braking tongues can be independent: the charging lever can be controlled directly by the box-back etc. 75

It is not necessary that the lever 50 should be arranged towards the end of the lay. It can be allowed to take its usual position near the lay sword, without the ejecting tongue 51 having to be altered; it is only 80 necessary for this to transmit the movement of a point of the end of this tongue as far as the lever 50, by means of another suitable lever. It is not necessary that the principal braking tongue should be pivoted at a point 85 some distance from the end of the box-back. A tongue of the usual type, pivoted near the pin 8 suits very well for acting on a lever 50 arranged in its usual position.

It can be foreseen that a case may arise, in 90 exceptional circumstances, when an expelled shuttle is caught between the box-back and the lay sword 3, and when the abutment 27 is already in engagement with the breast beam (due to bad fitting of the loom). In 95 order to avoid damage of a member, the tail piece 28 of the box-back comprises two members, one of which can slide into the other (like a telescope), the sliding action, which is opposed by a spring, only taking place in 100 case of any excessive effort being applied on the abutment 27. This tail piece 28 may also comprise two hinged articulated members; it may rest upon a pivoted plate, mounted resiliently; or in short it is possible to employ any arrangement capable of yielding 105 without breaking in case of any excessive effort.

The mechanism described can be adapted to looms provided with a loose reed. 110

The operation of the mechanism, instead of being controlled by the weft fork, as has been described, may be controlled with the same ease by any weft-feeler arrangement whatever for changing the shuttle in service when it has become exhausted. In fact, to produce the release of the mechanism, it suffices to displace a small rod or bar, almost horizontal and similar to the member 24 fixed on the weft fork, in front of the lever 23. A very small effort and a very small displacement suffice and this renders the control easy by any testing device, generally by any control device which transmits its orders to such a small rod or bar. For example, such a member can take the place of the small bar 24 of the weft fork: it can also co-act with it, acting on the same lever 23 of the change shaft 22 for unlocking: it can also act on any other lever arranged elsewhere and differ- 125 130

ently for acting upon the principal detent 19 in a similar manner to that which has been described. It is necessary, however, to ensure that this new member will be acted upon 5 at every other beat of the loom by means of the safety cam described, as the lever 56 and the roller 54 described do on the tail piece of the weft fork. In this way, the changing 10 of the shuttle may be produced after a certain number of beats of the loom for example, or by any other predetermined means, by the aid of mechanism or by hand, without ever having to fear untimely operation, which the safety cam prevents.

15 I claim:

1. Automatic shuttle-changing mechanism for looms operating without altering the speed of the loom, comprising in combination a shuttle box having a back which is adapted 20 to be deflected inwardly and a front which is adapted to be raised, a spring tending to deflect said box back inwardly, a detent maintaining said box back in the normal position, said detent being adapted to be released 25 during a short instant of each beat of the loom when the lay is in the forward or beating up position, a fixed abutment adapted to restore said box back to normal position and means for releasing said detent retaining said 30 box back, said means operating by a resiliently transmitted impulse which is prevented at every other beat of the loom.

2. Automatic shuttle-changing mechanism for looms operating without altering the speed of the loom, comprising in combination a shuttle box having a back which is adapted 35 to be deflected inwardly and a front which is adapted to be raised, a spring tending to deflect said box back inwardly, a detent maintaining said box back in the normal position against the action of said spring, said detent being adapted to be released during a short instant of each beat of the loom when the lay is in the forward or beating up position, a 40 fixed abutment adapted to restore said box back to normal position and means for releasing said detent retaining said box back, said means comprising a resiliently operated member situated on the lay itself and operated in the forward or beating up position 45 of the loom by an impulse produced by an abutment controlled by the failing of the weft and adapted to be forcibly diverted from its normal direction of operation at every other 50 beat of the loom.

3. Automatic shuttle-changing mechanism for looms operating without altering the speed of the loom, comprising in combination a shuttle box having a back which is 55 adapted to be deflected inwardly and a front which is adapted to be raised, means controlled by the box-back for locking the box-front when at rest, a spring tending to deflect said box-back inwardly, a detent maintaining said box-back in the normal position 60

against the action of said spring, said detent being adapted to be released during a short instant of each beat of the loom when the lay is in the forward or beating up position, means controlled by said box-back when deflected for unlocking and raising said box-front, means for locking said box-front in the raised position, a fixed abutment adapted to restore said box-back to normal position, means controlled by said box-back when being restored to normal position for unlocking said raised box-front and means controlled by the failing of the weft for releasing said detent retaining said box-back.

4. Automatic shuttle-changing mechanism for looms operating without altering the speed of the loom, comprising in combination a shuttle box having a back which is adapted to be deflected inwardly and a front which is adapted to be raised, a spring tending to deflect said box-back inwardly, a detent maintaining said box-back in the normal position against the action of said spring, said detent being adapted to be released during a short instant of each beat of the loom when the lay is in the forward or beating up position, means for releasing said detent retaining said box-back, said means operating by a resiliently transmitted impulse which is prevented at every other beat of the loom, a fixed abutment adapted to restore said box-back to normal position, a braking member for retaining the ejected shuttle, a detent for maintaining said braking member in the deviated position whilst the box-back is being restored to normal position and means for releasing immediately said detent of said braking member.

5. Automatic shuttle-changing mechanism for looms operating without altering the speed of the loom, comprising in combination a shuttle box having a back which is adapted to be deflected inwardly and a front which is adapted to be raised, means controlled by the box-back for locking the box-front when at rest, a spring tending to deflect said box-back inwardly, a detent maintaining said box-back in the normal position against the action of said spring, said detent being adapted to be released during a short instant of each beat of the loom when the lay is in the forward or beating up position, means for releasing said detent retaining said box-back, said means operating by a resiliently transmitted impulse produced by the weft fork and prevented at every other beat of the loom, means controlled by said box-back when deflected for unlocking and raising said box-front, means for locking said box-front in the raised position, a fixed abutment adapted to restore said box-back to normal position, means controlled by said box-back when being restored to normal position for unlocking said raised box-front, a braking member for retaining the ejected shuttle, a detent for main-

taining said braking member in the deviated position whilst the box-back is being restored to normal position and means for releasing immediately said detent of said braking member.

6. Automatic shuttle-changing mechanism for looms operating without altering the speed of the loom, comprising in combination a shuttle box having a back which is adapted to be deflected inwardly and a front which is adapted to be raised, means controlled by the box-back for locking the box-front when at rest, a spring tending to deflect said box-back inwardly, a detent maintaining said box-back in the normal position against the action of said spring, said detent being adapted to be released during a short instant of each beat of the loom when the lay is in the forward or beating up position, means for releasing said detent retaining said box-back, said means operating by a resiliently transmitted impulse which is prevented from operating at every other beat of the loom, means controlled by said box-back when deflected for unlocking and raising said box-front, means for locking said box-front in the raised position, a fixed abutment adapted to restore said box-back to normal position, means controlled by said box-back when being restored to normal position for unlocking said raised box-front, a braking member for retaining the ejected shuttle and means operated by said braking member for allowing the shuttle driving picker to be moved back into normal position until after the charging of a new shuttle.

7. Automatic shuttle-changing mechanism for looms operating without altering the speed of the loom, comprising in combination a shuttle box having a back which is adapted to be deflected inwardly and a front which is adapted to be raised, means controlled by the box-back for locking the box-front when at rest, a spring tending to deflect said box-back inwardly, a detent maintaining said box-back in the normal position against the action of said spring, said detent being adapted to be released during a short instant of each beat of the loom when the lay is in the forward or beating up position, means for releasing said detent retaining said box-back, said means operating by a resiliently transmitted impulse which is prevented from operating at every other beat of the loom, means controlled by said box-back when deflected for unlocking and raising said box-front, means for locking said box-front in the raised position, a fixed abutment adapted to restore said box-back to normal position, means controlled by said box-back when being restored to normal position for unlocking said raised box-front, a braking member for retaining the ejected shuttle and a pivoted lever adapted to be operated when the lay approaches the breast beam of the loom to move back the

shuttle driving picker during the charging of a new shuttle.

8. Automatic shuttle-changing mechanism for looms operating without altering the speed of the loom, comprising in combination a shuttle box having a back which is adapted to be deflected inwardly and a front which is adapted to be raised, means controlled by the box-back for locking the box-front when at rest, a spring tending to deflect said box-back inwardly, a detent maintaining said box-back in the normal position against the action of said spring, said detent being adapted to be released during a short instant of each beat of the loom when the lay is in the forward or beating up position, means for releasing said detent retaining said box-back, said means operating by a resiliently transmitted impulse which is prevented from operating at every other beat of the loom, means controlled by said box-back when deflected for unlocking and raising said box-front, means for locking said box-front in the raised position, a fixed abutment adapted to restore said box-back to normal position, means controlled by said box-back when being restored to normal position for unlocking said raised box-front, a braking member for retaining the ejected shuttle and a resiliently mounted tongue on the box-back adapted to absorb the shock of the ejected shuttle and to guide it into the inclined ejection passage.

9. Automatic shuttle-changing mechanism for looms operating without altering the speed of the loom, comprising in combination a shuttle box having a back which is adapted to be deflected inwardly and a front which is adapted to be raised, means controlled by the box-back for locking the box-front when at rest, a spring tending to deflect said box-back inwardly, a detent maintaining said box-back in the normal position against the action of said spring, said detent being adapted to be released during a short instant of each beat of the loom when the lay is in the forward or beating up position, means for releasing said detent retaining said box-back, said means operating by a resiliently transmitted impulse which is prevented from operating at every other beat of the loom, means controlled by said box-back when deflected for unlocking and raising said box-front, means for locking said box-front in the raised position, a fixed abutment adapted to restore said box-back to normal position, means controlled by said box-back when being restored to normal position for unlocking said raised box-front, a braking member for retaining the ejected shuttle, a supply magazine and means for forcing a new shuttle out of said supply magazine, said means comprising a swinging member so actuated that it regulates the speed of exit of said shuttle from said supply magazine.

10. Automatic shuttle-changing mechanism for looms operating without altering the speed of the loom, comprising in combination a shuttle box having a back which is adapted to be deflected inwardly and a front which is adapted to be raised, means controlled by the box-back for locking the box-front when at rest, a spring tending to deflect said box-back inwardly, a detent maintaining said box-back in the normal position against the action of said spring, said detent being adapted to be released during a short instant of each beat of the loom when the lay is in the forward or beating up position, means for releasing said detent retaining said box-back, said means operating by a resiliently transmitted impulse which is prevented from operating at every other beat of the loom, means controlled by said box-back when deflected for unlocking and raising said box-front, means for locking said box-front in the raised position, a fixed abutment adapted to restore said box-back to normal position, means controlled by said box-back when being restored to normal position for unlocking said raised box-front, a braking member for retaining the ejected shuttle and a supply magazine mounted on the breast beam of the loom comprising means for retaining the shuttle whilst waiting for the next charging operation and means for retaining the upper shuttles during the charging operation so as to allow the re-entry into the magazine of an ejected shuttle pushed back by the lay of the loom when said shuttle has been ejected at the wrong time.

11. Automatic shuttle-changing mechanism for looms operating without altering the speed of the loom, comprising in combination a shuttle box having a back which is adapted to be deflected inwardly and a front which is adapted to be raised, means controlled by the box-back for locking the box-front when at rest, a spring tending to deflect said box-back inwardly, a detent maintaining said box-back in the normal position against the action of said spring, said detent being adapted to be released during a short instant of each beat of the loom when the lay is in the forward or beating up position, means controlled by said box-back when deflected for unlocking and raising said box-front, means for locking said box-front in the raised position, a fixed abutment adapted to restore said box-back to normal position, means controlled by said box-back when being restored to normal position for unlocking said raised box-front, means for releasing said detent retaining said box-back, said means operating by a resiliently transmitted impulse produced by the weft fork and prevented at every other beat of the loom, a taking-up regulator and means

for momentarily suppressing the action of said regulator.

12. Automatic shuttle-changing mechanism for looms operating without altering the speed of the loom, comprising in combination a shuttle box having a back which is adapted to be deflected inwardly and a front which is adapted to be raised, means controlled by the box-back for locking the box-front when at rest, a spring tending to deflect said box-back inwardly, a detent maintaining said box-back in the normal position against the action of said spring, said detent being adapted to be released during a short instant of each beat of the loom when the lay is in the forward or beating up position, means for releasing said detent retaining said box-back, said means comprising a resiliently operated member situated on the lay itself and operated in the forward or beating up position of the loom by an impulse produced by an abutment controlled by the failing of the weft, means for stopping momentarily the action of the taking-up regulator of the loom during several beats of the loom, means controlled by said box back when deflected for unlocking and raising said box-front, means for locking said box-front in the raised position, a fixed abutment adapted to restore said box-back to normal position, means controlled by said box-back when being restored to normal position for unlocking said raised box-front, a braking member for retaining the ejected shuttle, adapted to remain in the deviated position whilst the box-back is being restored to normal position, a resiliently mounted tongue on the box-back adapted to absorb the shock of the ejected shuttle and to guide it into the inclined ejection passage, a magazine mounted on the breast beam of the loom comprising means for retaining the shuttle in position until the charging operation has been effected, and a swinging member adapted to force a new shuttle out of said supply magazine at regulated speed and means for forcibly returning the shuttle-driving picker to normal position after each pick of the loom.

In testimony whereof I have hereunto affixed my signature.

MAURICE CHARLES HENRI OCTAVE LECOCQ.
